UNITED STATES PATENT OFFICE.

ALEXANDER FERDINAND VICTOR, OF ELMIRA, NEW YORK, ASSIGNOR TO WHITE LILY WASHER COMPANY, OF DAVENPORT, IOWA, A CORPORATION OF IOWA.

GEARING FOR WASHING-MACHINES.

No. 895,518.

Specification of Letters Patent.

Patented Aug. 11, 1908.

Application filed April 6, 1907. Serial No. 308,085.

To all whom it may concern:

Be it known that I, ALEXANDER FERDINAND VICTOR, a subject of the King of Sweden, and a resident of Elmira, in the county of Chemung and State of New York, have invented certain new and useful Improvements in Gearing for Washing-Machines, of which the following is a full, clear, and exact description.

10 My invention relates to gearing for washing machines, and particularly to that class of machines in which the cleansing of the wash is accomplished by a rotary reciprocal stirrer-shaft extending centrally down through the lid or cover and provided with a head on the lower end.

The object of my invention is to provide simple and comparatively inexpensive mechanism for actuating the stirrer-shaft and head, which, in a very direct manner causes a fly-wheel to rapidly revolve, and in return is affected and materially assisted by the momentum thereof to overcome the resistance resulting from the ordinary operation of the machine, and particularly at the moment of reversion of the movement of the stirrer-head. And a further object is to permit certain elements of said mechanism to be easily disconnected when it is desired to open the tub of the machine, or connected when said tub is closed and it is desired to operate the machine, without necessitating the exercise of any mechanical ability other than that possessed by the ordinary person. This I accomplish by the means hereinafter fully described and as particularly pointed out in the claims.

In the drawings:—Figure 1 is a side elevation of a washing machine having my improvements applied thereto. Fig. 2 is a plan view of the same. Fig. 3 is a horizontal section taken on dotted line 3, 3, Fig. 1, looking in the direction indicated by the arrows.

Referring to the drawings, A represents a tub supported by legs a, and provided with a lid or cover B the straight edge of which is hinged to a permanent top strip b secured to the top edges of the tub, as shown. At about the center of the tub, I journal a rotary reciprocal stirrer-shaft C in suitable bearings in the lid, the end of which above said lid has a pinion c suitably secured thereto, and the lower end of which within the tub has a stirrer-head d thereon. This pinion c is en-

gaged by a horizontally disposed reciprocal internal gear D, whose bow is suitably journaled to a pivotal stud e secured to and projecting up from a screw-plate secured to said lid in such position that an imaginary line intersecting the center of said stirrer-shaft and pivotal-stud will be at right angles to the hinged edge of the cover.

* Journaled in bearings in the ends of brackets f and f' secured to and projecting from the side of the tub, is a vertical rock-shaft E, 65 whose axis is in the same vertical plane as the axes of the stirrer-shaft C and pivotal stud e. The upper end of this rock-shaft has one end of a lever F (of the second class) hinged thereto by means of a transverse pintle, so 70 that said lever can be moved into a horizontal position over the top of the tub and so that it will lodge between two pins g, g, projecting vertically from the segmental rim portion of the internal gear. Thus by grasping the handle H' projecting up from the end of lever F opposite the rock-shaft and moving the lever back and forth, the internal segmental-gear and through it the stirrer-shaft are given a rotary reciprocal movement. 80

The lower end of rock-shaft E extends below the plane of the bottom of the tub, and has an arm G secured thereto, which projects under said tub. The portion of said arm under the tub is provided with a longitudinally elongated slot h; and a stud or pin i projecting down from a large gear H, extends down through this slot. Gear H is loosely journaled on the stud i depending down from a suitable plate secured to the bottom of the tub, and when arm G is moved back and forth a rotary motion is imparted to said gear, which latter through the medium of a pinion J revolves a vertical spindle K, which at a point below the plane of arm G has a fly-wheel L secured fast thereto. The lower end of this spindle K is journaled in a boss made at the intersection of the cross-braces k, and the upper end thereof in a suitable plate m secured centrally to the bottom of the tub, 100 and when gear H revolves, the fly-wheel is revolved at a much greater speed, and its momentum is utilized to greatly assist in the operation of the machine.

When it is desired to open the lid of the tub, all that it is necessary to do is to lift the lever out of engagement with the segmental internal gear, and when the lid is closed and

it is desired to operate the machine, the lever can be easily lowered into engagement with said internal gear again.

What I claim as new is:—

- it is desired to operate the machine, the lever can be easily lowered into engagement with said internal gear again.

What I claim as new is:—

  1. Mechanism for driving a washing machine comprising a rotary reciprocal shaft, a vertical rock-shaft, a lever projecting from said rock-shaft over the top of the rotary reciprocal shaft and means for imparting the motion of said lever to said rotary reciprocal shaft.
  2. Mechanism for driving a washing machine comprising a rotary reciprocal shaft, a vertical rock-shaft, a lever projecting from and hinged to said rock-shaft over the top of the rotary reciprocal shaft and means for imparting the motion of said lever to said rotary reciprocal shaft.
  3. Mechanism for driving a washing machine comprising a rotary reciprocal shaft, a pinion thereon, a horizontally disposed rotary reciprocal segmental gear pivoted adjacent to said shaft and engaging said pinion, and a lever adapted to engage and reciprocate said segmental gear and pivoted at a point beyond its engagement with said segmental gear.
  4. Mechanism for driving a washing machine comprising a rotary reciprocal shaft, a pinion thereon, a rotary reciprocal segmental gear pivoted adjacent to said shaft and engaging said pinion, a vertically disposed rock-shaft, and a lever hinged to said rock-shaft and adapted to extend over the top of the rotary reciprocal shaft and engage said segmental gear.
  5. Mechanism for driving a washing machine comprising a rotary reciprocal shaft, a pinion thereon, a rotary reciprocal segmental internal gear having an upwardly projecting pin and pivoted adjacent to and engaging said pinion, a vertically disposed rock-shaft, and a lever hinged to said rock-shaft and adapted to extend over the top of the rotary reciprocal shaft and engage said segmental gear.
  6. Mechanism for driving a washing machine comprising a rotary reciprocal shaft, a vertical rock-shaft, devices for actuating said rock-shaft and rotary reciprocal shaft simultaneously, a fly-wheel and means actuated by said rock-shaft for actuating said fly-wheel.
  7. Mechanism for driving a washing machine comprising a rotary reciprocal shaft, a vertical rock-shaft, devices for actuating said rock-shaft and rotary reciprocal shaft simultaneously, a horizontally disposed fly-wheel located under said rotary reciprocal shaft and means actuated by said rock-shaft for actuating said fly-wheel.
  8. Mechanism for driving a washing machine comprising a rotary reciprocal shaft, a vertical rock-shaft, devices for actuating said rock-shaft and rotary reciprocal shaft
  9. Mechanism for driving a washing machine comprising a rotary reciprocal shaft, gearing for operating the same, a vertical rock-shaft, a lever for actuating said rock-shaft and gearing simultaneously, a fly-wheel, and means actuated by said rock-shaft for actuating said fly-wheel.
  10. Mechanism for driving a washing machine comprising a rotary reciprocal shaft, gearing for operating the same, a vertical rock-shaft, a lever for actuating said rock-shaft and gearing simultaneously, a horizontally disposed fly-wheel located below said rotary reciprocal shaft, and means actuated by said rock-shaft for actuating said fly-wheel.
  11. Mechanism for driving a washing machine comprising a rotary reciprocal shaft, gearing for operating the same, a vertical rock-shaft, a lever for actuating said rock-shaft and gearing simultaneously, a slotted arm projecting from the lower end of said rock-shaft, a horizontally disposed gear journaled under said rotary reciprocal shaft and actuated by said arm, a vertical spindle adjacent to said gear, a pinion thereon engaged by said gear, and a fly-wheel mounted on said spindle.
  12. Mechanism for driving a washing machine comprising a rotary reciprocal shaft, gearing for operating the same, a vertical rock-shaft, a lever hinged to the top of the rock-shaft for actuating said rock-shaft and gearing simultaneously, a fly-wheel and means actuated by said rock-shaft for actuating said fly-wheel.
  13. Mechanism for driving a washing machine comprising a rotary reciprocal shaft, gearing for operating the same, a vertical rock-shaft, a lever hinged to the top of the rock-shaft for actuating said rock-shaft and gearing simultaneously, a horizontally disposed fly-wheel located below said rotary reciprocal shaft and means actuated by said rock-shaft for actuating said fly-wheel.
  14. Mechanism for driving a washing machine comprising a rotary reciprocal shaft, gearing for operating the same, a vertical rock-shaft, a lever hinged to the top of the rock-shaft for actuating said rock-shaft and gearing simultaneously, a slotted arm projecting from the lower end of said rock-shaft, a horizontally disposed gear journaled under said rotary reciprocal shaft and actuated by said arm, a vertical spindle adjacent to said gear, a pinion thereon engaged by said gear, and a fly-wheel mounted on said spindle.
  15. A mechanism for driving a washing

- machine comprising a rotary reciprocal shaft, a pinion thereon, a rotary reciprocal segmental gear pivoted adjacent to and engaging said pinion, a vertical rock-shaft, a lever hinged to said rock-shaft for actuating said rock-shaft and rotary reciprocal shaft simultaneously, a fly-wheel, and means actuated by said rock-shaft for actuating said fly-wheel.
- 10 16. Mechanism for driving a washing machine comprising a rotary reciprocal shaft, a pinion thereon, a rotary reciprocal segmental gear pivoted adjacent to and engaging said pinion, a vertical rock-shaft, a lever hinged to said rock-shaft for actuating said rock-shaft and rotary reciprocal shaft simultaneously, a horizontally disposed fly-wheel located below said rotary reciprocal shaft, and means actuated by said rock-shaft for actuating said fly-wheel.
- 15 17. Mechanism for driving a washing ma-
- chine comprising a rotary reciprocal shaft, a pinion thereon, a rotary reciprocal segmental gear pivoted adjacent to and engaging said pinion, a vertical rock-shaft, a lever hinged to said rock-shaft for actuating said rock-shaft and rotary reciprocal shaft simultaneously, a slotted arm projecting from the lower end of said rock-shaft, a horizontally disposed gear journaled below said rotary reciprocal shaft and actuated by said arm, a vertical spindle below said shaft a pinion thereon engaged by said gear, and a fly-wheel mounted on said spindle.
- 20

In testimony whereof I have hereunto set my hand and seal this 18th day of March, 1907.

ALEXANDER FERDINAND VICTOR. [L. s.]
